DUAL SOLENOID CONTROLLED APPARATUS FOR PREVENTING RELEASE OF CONTAMINANTS FROM AN INTERNAL COMBUSTION ENGINE

Fred E. McKinley, Paramount, Calif.

Application March 19, 1956, Serial No. 572,276

10 Claims. (Cl. 123—119)

The present invention relates generally to the field of internal combustion engines and more particularly to a novel apparatus for preventing the release of contaminants from the exhaust thereof.

It is well known that the exhaust gases issuing from the internal combustion engines of automotive vehicles constitute a prime source of the so-called "smog" which exists in and around the principal population centers of the country. The harmful effects of this smog upon both animate and inanimate objects is likewise very well known. Although many forms of apparatus for preventing the release of contaminants from the exhaust gases of such engines have been heretofore proposed, such devices have for various reasons proven to be unsatisfactory and accordingly are not now in general usage.

It is a major object of the present invention to provide an effective apparatus for preventing the release of contaminants from the exhaust of an internal combustion engine.

Another object of the invention is to provide an apparatus of the aforescribed nature which may be readily installed upon the engine of any conventional automotive vehicle.

It is another object of the invention to provide apparatus of the aforescribed nature which includes means for re-cycling exhaust gas through the intake manifold of the engine during deceleration.

Another object is to provide apparatus of the aforescribed nature that is simple in design and rugged of construction whereby it may afford a long and trouble-free service life.

It is yet another object to provide apparatus of this nature that is foolproof and entirely automatic in operation.

A further object is to provide apparatus of the aforescribed nature which does not in any way effect the operation of the engine during other than deceleration conditions.

Another object is to provide apparatus of the aforescribed nature which is compact in size and light in weight.

These and other objects and advantages of the present invention will become apparent from the following detailed description, when taken in conjunction with the appended drawings, wherein:

Figure 1 is a partially diagrammatic side elevational view of a preferred form of apparatus embodying the present invention mounted upon a conventional internal combustion engine;

Figure 2 is a view similar to Figure 1 but showing the parts of the apparatus during deceleration of said engine;

Figure 3 is an enlarged fragmentary vertical sectional view showing a detail of said apparatus;

Figure 4 is a circuit diagram which may be utilized with said apparatus; and

Figure 5 is an enlarged view of a component of said apparatus.

2

Referring to the drawings, the preferred form of apparatus embodying the present invention is shown mounted upon the side of a conventional internal combustion engine having an intake manifold I, an exhaust manifold E, a generator G and a carburetor C. The exhaust manifold E is connected to a tail pipe T. The carburetor C is operated by means of an accelerator pedal A.

The carburetor C is carried by a hollow support 10. The front side of this carburetor support 10 is connected to the upper end of a curved by-pass pipe 12. The lower end of the by-pass pipe 12 is rigidly secured to a T-fitting 14. The upper end of the T-fitting 14 is connected to a flanged opening 16 formed on the exhaust manifold E. The lower end of the T-fitting 14 is rigidly secured to the front of the tail pipe T. A fuel shut-off valve 20 is mounted within the carburetor support 10 above the flanged opening 11 so as to control communication between the carburetor C and the intake manifold I. A re-cycling valve 22 is also mounted within the carburetor support 10 adjacent the flanged opening 11. This re-cycling valve 22 controls communication between the by-pass pipe and the intake manifold I.

Referring to Figure 1, during operation of the engine E other than deceleration, the fuel shut-off valve 20 will be arranged in an open position while the re-cycling valve 22 will be arranged in a closed position. Accordingly, the carburetor C will be in free communication with the intake manifold I while the re-cycling valve 22 will prevent the flow of re-cycled exhaust gas into the intake manifold I. Referring now to Figure 2, during deceleration of the engine, however, the fuel shut-off valve 20 will be arranged in a closed position while the re-cycling valve 22 will be opened. Accordingly, during deceleration of the engine, the closed fuel shut-off valve 20 will prevent the flow of fuel from the carburetor C to the intake manifold I while at the same time the opened re-cycling valve 22 will permit exhaust gases to be re-cycled from the exhaust manifold E into the intake manifold I.

More particularly, referring to Figures 1 and 3, both the fuel shut-off valve 20 and the re-cycling valve 22 may be of the butterfly type. Other types of valves, however, may also prove satisfactory. The fuel shut-off valve 20 is pivotally supported within the carburetor support 10 by means of a horizontal shaft 26. The re-cycling valve 22 is likewise pivotally supported within the carburetor support 10 by a second horizontal shaft 28. Externally of the carburetor support 10, the shaft 26 is keyed to a crank 30. The horizontal shaft 28 of the re-cycling valve 22 is likewise keyed to a second crank 32 aligned with the first crank 30. The free ends of these cranks 30 and 32 are pivotally interconnected by a rigid lever 34. The shaft 26 is also keyed to a downwardly extending toggle arm 36. The lower end of this toggle arm is pivotally connected to the intermediate portion of a horizontally extending plunger rod 40. The two end portions of this plunger rod 40 are affixed to the armatures (not shown) of a pair of electric solenoids 42 and 44. These solenoids 42 and 44 are rigidly affixed to the carburetor support 10. The lower end of the toggle arm 36 is also secured to the lower end of a tension spring 46. The upper end of this tension spring 46 is rigidly secured to the side of the carburetor support 10.

An electric switch 50 is secured to a bracket 52 depending from the vehicle's floor board 54. The accelerator pedal A is mounted rearwardly of this bracket 52 and is connected to the carburetor C by suitable conventional linkage. This linkage includes a horizontally extending, longitudinally movable rod 56. A bumper member 58 is rigidly affixed to this rod 56. The upper

end of the bumper member 58 carries a set screw 60. The front end of the set screw 60 is aligned with an actuator button 62 that protrudes from the rear of the switch 50. As indicated in Figure 1, at such time as the accelerator pedal is depressed, the set screw 60 will be spaced rearwardly and out of engagement with the microswitch button 62. Referring now to Figure 2, when the accelerator pedal A is released, however, the rod 56 will be moved to its forward position so that the set screw 60 engages and depresses the microswitch button 62.

A low output circuit closing switch 70 forms another component of the apparatus. As indicated in Figure 4, this switch 70 includes a switch element 74 which is normally biased towards a closed position by a suitable spring 76. The switch element 74 is adapted to be retained in an open position upon adequate energization of the windings 78 of a solenoid 80, the armature 82 of this solenoid being connected to the switch 74. One side of the windings 78 are grounded by a lead 84 while the other side is connected by a lead 86 to the ungrounded terminal of the generator G. One side of the switch element 74 is connected to the windings of the right-hand solenoid 42 by a lead 88. The opposite side of the switch element 74 is connected by a lead 90 to the vehicle's battery 92.

Referring now to Figure 5, the solenoids 42 and 44 are of identical construction. They incorporate an electric switch element 94 that is normally biased to a closed position by a compression spring 95. Each end of the plunger 40 is formed with an actuating pin 96. When the windings 98 of the solenoid are energized so as to cause the plunger to be retracted therewith, the actuating pin 96 will move the switch element 78 to an open position, as indicated in this figure. The electric current flowing to the windings 98 from the battery 92 will thereby be automatically cut off.

Referring again to Figures 1 and 2, the upper terminal 100 of the switch 50 is connected by a lead 102 to the windings of the left-hand solenoid 44. The other side of these windings are grounded by a lead 104. The center terminal 106 of the switch 50 is connected by a lead 108 to the vehicle's battery 92. The lower terminal 110 of the switch 50 is connected by a lead 112 to the right-hand solenoid 42, the lead 112 intersecting the lead 88 from the low output closing switch 70. The other side of these windings are grounded by a lead 114.

In the operation of the aforescribed apparatus and referring to Figure 1, assuming the vehicle's driver is exerting downward pressure upon the accelerator pedal A, the set screw 60 of the bumper member 58 will be spaced rearwardly from the switch button 62. Accordingly, current will be free to flow from the battery 92 through lead 108 to the center terminal 106 of the switch 50. At this time the center terminal 106 will be connected to the lower terminal 110 and accordingly this current will be free to flow through lead 112 to the windings of the right-hand solenoid 42. This current will not actually flow to the solenoid windings, however, inasmuch as the solenoid's switch element 94 will be in an open position. Assuming that the rotational speed of the generator G is above idling at this time, the switch element 74 of the low output circuit closing switch 70 will likewise be open. Thus, current cannot flow from lead 90 through to lead 88 to the windings of the solenoid 42. The plunger rod 40 and hence the toggle arm 36 are retained in their position of Figure 1 by the toggle spring 46. Accordingly, the fuel shut-off valve 20 will be maintained in an open position while the recycling valve 22 will be held in a closed position. At this time, normal communication will exist between the carburetor C and the intake manifold I, while the flow of exhaust gases into the intake manifold will be effectively blocked by the closed re-cycling valve 22.

Referring now to Figure 2 and assuming that the vehicle is undergoing forward motion, when the driver re-

leases the accelerator pedal A so as to decelerate, the set screw 60 will engage and depress the switch button 62. This will cut off the flow of current to the lower terminal 110 of the microswitch 50 from the center terminal 106, and instead connect the center terminal 106 to the upper terminal 100. Accordingly, current will be free to flow from the battery 92 through lead 102 to the windings of the left-hand solenoid 44. The latter will be thereby energized so as to retract the plunger rod 40 into the solenoid 44. As the plunger rod is so retracted, its actuating pin 96 will open its switch element 94 and thereby cut off further flow of current to these windings. Once the plunger rod 40 has been urged into its position of Figure 2, the toggle spring 46 will positively retain it therein. This movement of the plunger rod 40 will close the fuel shut-off valve 20 and concurrently open the re-cycling valve 22. Accordingly, the flow of fuel from the carburetor C into the intake manifold I will cease. Concurrently, exhaust gases will be free to recycle from the exhaust manifold E into the intake manifold I. Under these conditions, the contaminants usually produced by the conventional engines during deceleration due to the existence of an excess of fuel within the combustion chambers will not be produced. Additionally, the intake manifold I will be maintained in a heated and dry condition by the re-cycled exhaust gases. Accordingly, when the fuel shut-off valve 20 is again opened, the fuel flowing into the intake manifold will be sufficiently vaporized as to undergo immediate combustion. The introduction of exhaust gas within the intake manifold I below the fuel shut-off valve 20 also prevents the fuel from being drawn around the periphery of the fuel shut-off valve due to the high vacuum normally created within the intake manifold during deceleration of the engine.

Assuming that the vehicle comes to a stop with the accelerator pedal released, the electric current generated by the generator G will gradually decrease. As the current decreases, the spring 76 of the low output circuit closing switch 70 will eventually overcome the weakening force of the windings 80 of the solenoid 78 whereby the switch element 74 will move to a closed position. Electric current will then flow from the battery 92 through leads 90 and 88 to the windings of the right-hand solenoid 42 so as to energize these windings. Upon such energization, the plunger rod 40 will be returned to the right to its original position so as to thereby re-open the fuel shut-off valve 20 and concurrently close the re-cycling valve 22. The closing movement of the plunger rod 40 will serve to open its switch element 94 whereby the flow of current to the windings of the solenoid 42 will be cut off.

Assuming that the vehicle is again accelerated after a deceleration period without coming to a stop, the switch element 74 of the low output circuit closing switch 70 will not be closed. When the accelerator pedal A is again depressed, the set screw 60 will be retracted from the switch button 62. Accordingly, current from the battery 92 will no longer flow from the center terminal 106 of the switch to the upper terminal 100 thereof but instead will flow from the center terminal to the lower terminal 110. This will effect momentary energization of the right-hand solenoid 42 so as to return the plunger rod 40 to the right. In this manner, the fuel shut-off valve 20 will be re-opened while the re-cycling valve 22 will be concurrently closed.

Although the intake manifold I is shown as being connected to a conventional carburetor, it will be apparent that various other fueling devices may be employed such as a conventional fuel injection arrangement. It will also be apparent that various other modifications and changes may be made with respect to the foregoing description without departing from the spirit of the invention or the scope of the following claims.

I claim:

1. Apparatus for preventing release of contaminants from the exhaust of an internal combustion engine during deceleration, said engine including an intake manifold, a carburetor and an accelerator, comprising: a fuel shut-off valve interposed between said carburetor and said intake manifold; fluid conduit means interconnecting said exhaust and said intake manifold; a re-cycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said re-cycling valve to an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected to said electric switch; a second electric switch interposed in said electric conduit means and which when closed will effect energization of said first solenoid, said second electric switch normally being maintained open; and means for automatically closing said second electric switch when the rotational speed of said engine falls below a predetermined value whereby said first solenoid means will be energized even though said accelerator is released.

2. Apparatus for preventing release of contaminants from the exhaust of an internal combustion engine during deceleration, said engine including an intake manifold, a carburetor and an accelerator, comprising: a fuel shut-off valve interposed between said carburetor and said intake manifold; fluid conduit means interconnecting said exhaust and said intake manifold; a re-cycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said re-cycling valve to an open position; spring means for retaining said fuel shut-off valve in an open position and said re-cycling valve in a closed position or alternately retaining said fuel shut-off valve in a closed position and said re-cycling valve in an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected to said electric switch; a second electric switch interposed in said electric conduit means and which when closed will effect energization of said first solenoid, said second electric switch normally being maintained open; and means for automatically closing said second electric switch when the rotational speed of said engine falls below a predetermined value whereby said first solenoid means will be energized even though said accelerator is released.

3. Apparatus for preventing release of contaminants from the exhaust of an internal combustion engine during deceleration, said engine including an intake manifold, a carburetor and an accelerator; comprising: a fuel shut-off valve interposed between said carburetor and said intake manifold; fluid conduit means interconnecting said exhaust and said intake manifold; a recycling valve interposed in said fluid conduit means; first solenoid means operatively connected to said valves and which when energized concurrently moves said fuel shut-off valve to an

open position and said re-cycling valve to a closed position; second solenoid means operatively connected to said valves and which when energized concurrently moves said fuel shut-off valve to a closed position and said re-cycling valve to an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected with said electric switch; a second electric switch interposed in said electric conduit means and which when energized will effect energization of said first solenoid, said second electric switch normally being maintained open; means for automatically stopping the flow of electric current to said solenoid means after they have moved said valves from one position to another; and means for automatically closing said second electric switch when the rotational speed of said engine falls below a predetermined value whereby said first solenoid means will be energized even though said accelerator is released.

4. Apparatus for preventing release of contaminants from the exhaust of an internal combustion engine during deceleration, said engine including an intake manifold, a carburetor and an accelerator, comprising: a fuel shut-off valve interposed between said carburetor and said intake manifold; fluid conduit means interconnecting said exhaust and said intake manifold; a recycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said re-cycling valve to an open position; spring means for retaining said fuel shut-off valve in an open position and said re-cycling valve in a closed position or alternately retaining said fuel shut-off valve in a closed position and said re-cycling valve in an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected with said electric switch; a second electric switch interposed in said electric conduit means and which when energized will effect energization of said first solenoid, said second electric switch normally being maintained open; means for automatically stopping the flow of electric current to said solenoid means after they have moved said valves from one position to another; and means for automatically closing said second electric switch when the rotational speed of said engine falls below a predetermined value whereby said first solenoid means will be energized even though said accelerator is released.

5. Apparatus for preventing release of contaminants
60 from the exhaust of an internal combustion engine during deceleration, said engine including an intake manifold, a carburetor, a generator and an accelerator, comprising: a fuel shut-off valve interposed between said carburetor and said intake manifold; fluid conduit means
65 interconnecting said exhaust and said intake manifold; a re-cycling valve interposed in said fluid conduit means; first solenoid means operatively connected to said valves and which when energized concurrently moves said fuel shut-off valve to an open position and said recycling valve
70 to a closed position; second solenoid means operatively connected to said valves and which when energized concurrently moves said fuel shut-off valve to a closed position and said re-cycling valve to an open position; an electric switch operable by said accelerator for effecting
75 energization of said first solenoid means when said ac-

celerator is depressed and for alternately effecting energization of said second solenoid means when said accelerator is released; electric conduit means for conducting current to said solenoid means, said electric conduit means being connected with said electric switch; and a low output circuit closing switch interposed in said electric conduit means for conducting electric current to said first solenoid means only when the rotational speed of said engine falls below a predetermined value, said switch including a switch element, resilient means normally biasing said switch element closed, a solenoid having windings connected to said generator and an armature secured to said switch element.

6. Apparatus for preventing release of contaminants from the exhaust of an internal combustion engine during deceleration, said engine including an intake manifold, a carburetor, a generator and an accelerator, comprising: a fuel shut-off valve interposed between said carburetor and said intake manifold; fluid conduit means interconnecting said exhaust and said intake manifold; a re-cycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said recycling valve to an open position; toggle spring means for retaining said fuel shut-off valve in an open position and said re-cycling valve in a closed position or alternately retaining said fuel shut-off valve in a closed position and said re-cycling valve in an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected with said electric switch; and a low output circuit closing switch interposed in said electric conduit means for conducting electric current to said first solenoid means only when the rotational speed of said engine falls below a predetermined value, said switch including a switch element, resilient means normally biasing said switch element closed, a solenoid having windings connected to said generator and an armature secured to said switch element.

7. Apparatus for preventing release of contaminants from the exhaust of an internal combustion engine during deceleration, said engine including an intake manifold, a carburetor, a generator and an accelerator, comprising: a fuel shut-off valve interposed between said carburetor and said intake manifold; fluid conduit means interconnecting said exhaust and said intake manifold; a re-cycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said re-cycling valve to an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected with said electric switch; means for automatically stopping the flow of electric current to said solenoid means after they have moved said valves from one position to another; and a low output circuit closing switch interposed in said electric conduit means for conducting electric current to said first solenoid means only when the rotational speed of said engine

falls below a predetermined value, said switch including a switch element, resilient means normally biasing said switch element closed, a solenoid having windings connected to said generator and an armature secured to said switch element.

8. Apparatus for preventing release of contaminants from the exhaust of an internal combustion engine during deceleration, said engine including an intake manifold, a carburetor, a generator and an accelerator, comprising: a fuel shut-off valve interposed between said carburetor and said intake manifold; fluid conduit means interconnecting said exhaust and said intake manifold; a re-cycling valve interposed in said fluid conduit means; first solenoid means operatively connected to said valves and which when energized concurrently moves said fuel shut-off valve to an open position and said re-cycling valve to a closed position; second solenoid means operatively connected to said valves and which when energized concurrently moves said fuel shut-off valve to a closed position and said re-cycling valve to an open position; toggle spring means for retaining said fuel shut-off valve in an open position and said re-cycling valve in a closed position or alternately retaining said fuel shut-off valve in a closed position and said re-cycling valve in an open position; an electric switch operable by said accelerator for effecting energization of said first solenoid means when said accelerator is depressed and for alternately effecting energization of said second solenoid means when said accelerator is released; electric conduit means for conducting current to said solenoid means, said electric conduit means being connected with said electric switch; means for automatically stopping the flow of electric current to said solenoid means after they have moved said valves from one position to another; and a low output circuit closing switch interposed in said electric conduit means for conducting electric current to said first solenoid means only when the rotational speed of said engine falls below a predetermined value, said switch including a switch element, resilient means normally biasing said switch element closed, a solenoid having windings connected to said generator and an armature secured to said switch element.

9. Apparatus for preventing release of contaminants from the exhaust of an internal combustion engine during deceleration, said engine including an intake manifold, a carburetor and an accelerator, comprising: a fuel shut-off valve interposed between said carburetor and said intake manifold; fluid conduit means interconnecting said exhaust and said intake manifold; a re-cycling valve interposed in said fluid conduit means; electric solenoid means for moving said valves between a normal position wherein said fuel shut-off valve is open and said re-cycling valve is closed and a second position wherein said fuel shut-off valve is closed and said re-cycling valve is open; an electric switch operable by said accelerator whereby said solenoid means will be free to move said valves to their first position when said accelerator is released and said solenoid means will be free to move said valves to their second position when said accelerator is depressed; electric conduit means for conducting current to said solenoid means, said electric conduit means being connected to said electric switch; a normally open second electric switch interposed in said electric conduit means and which when closed will cause said solenoid means to move said valves to their first position; and means for automatically closing said second electric switch when the rotational speed of said engine falls below a predetermined value.

10. Apparatus for preventing release of contaminants from the exhaust of an internal combustion engine during deceleration, said engine including an intake manifold, a carburetor and an accelerator, comprising: a fuel shut-off valve interposed between said carburetor and said intake manifold; fluid conduit means interconnecting said exhaust and said intake manifold; a re-

9

cycling valve interposed in said fluid conduit means; electric solenoid means for moving said valves between a normal position wherein said fuel shut-off valve is open and said re-cycling valve is closed and a second position wherein said fuel shut-off valve is closed and said recycling valve is open; toggle spring means for retaining said valves in either position until they are again moved by said solenoid means; an electric switch operable by said accelerator whereby said solenoid means will be free to move said valves to their first position when said accelerator is released and said solenoid means will be free to move said valves to their second position when

5

10

said accelerator is depressed; electric conduit means for conducting current to said solenoid means, said electric conduit means being connected to said electric switch; a normally open second electric switch interposed in said electric conduit means and which when closed will cause said solenoid means to move said valves to their first position; and means for automatically closing said second electric switch when the rotational speed of said engine falls below a predetermined value.
